(57) CLAIM

The ornamental design for a printer, as shown and described.

DESCRIPTION

FIG. 1 is a perspective view of a printer;

FIG. 2 is a top view thereof;

FIG. 3 is a front view thereof;

FIG. 4 is a right side view thereof;

FIG. 5 is a left side view thereof;

FIG. 6 is a rear view thereof;

FIG. 7 is a perspective view thereof with a scanner cover in an open position; and,

FIG. 8 is a perspective view thereof with a display in a tilted position.

The broken lines are for illustrative purposes only and form no part of the claimed design.
